UNITED STATES PATENT OFFICE

2,533,239

IMPEDANCE TRANSFORMER FOR COAXIAL LINES

Alfred Walter Gent and Peter John Wallis, London, England, assignors, by mesne assignments, to International Standard Electric Corporation, New York, N. Y., a corporation of Delaware

Application January 5, 1946, Serial No. 639,290
In Great Britain November 16, 1944

Section 1, Public Law 690, August 8, 1946
Patent expires November 16, 1964

4 Claims. (Cl. 178—44)

1

The present invention relates to impedance transformers for transforming a coaxial conductor transmission line to another line having a different impedance and consequently at least one of the inner or outer conductors having different diameters.

Hitherto when joining two coaxial lines of different impedances and therefore of different transverse sectional dimensions, it has been usual to insert between the two lines a third length of line of uniform cross-section and substantially an odd number of quarter wave lengths long at the operating frequency. The characteristic impedance of the inserted quarter wave-length section is chosen to be the geometric mean of the impedances of the two lines between which it is inserted. A conspicuous feature of this arrangement is that there is necessarily a step in the size of at least one of the conductors at each end of the inserted section.

It is one object of the present invention to provide an impedance matching section for transforming the impedance of a coaxial conductor transmission line by transforming the diameter of at least one of the conductors gradually so that there are no discontinuous steps in conductor size anywhere.

This object is attained in accordance with the present invention by a section of coaxial transmission line having conductors whose diameters at one end are equal to the diameters of the conductors of said line and decrease or increase gradually in the direction of the desired conductor change to the other end of the said section so that there are no discontinuous steps in conductor size anywhere, and said section having an electrical length equal to an integral number of half-wavelengths at the operating frequency.

In practice, coaxial cables are usually employed for wide frequency bands and it is usually not sufficient to match a coaxial conductor transmission line as regards the impedance at one frequency only by an impedance transformer. It is another object of this invention to provide a coaxial section impedance matching transformer for transforming over a wide band of frequencies the impedance of a coaxial conductor transmission line to a line of another impedance. This object is attained in accordance with the present invention by providing a section of tapered coaxial conductor transmission line, having conductor diameters at one end equal to the diameters of the conductors of the line to which said section is connected, said section con-

2

ductors tapering in opposite directions with such tapers as to produce on said transmission line unity standing wave ratio at the mid band operating frequency and having an electrical length equal substantially to an integral number of half-wave-lengths at said mid-band frequency.

Another object of the invention is to provide an impedance transformer for transforming over a wide band of operating frequencies the

10 impedance of a coaxial conductor transmission line to a given impedance coaxial conductor transmission line having one conductor of predetermined diameter. Such a transformer according to this invention comprises two series 15 connected sections of tapered coaxial transmission line, one of said sections having conductor diameters at one end equal to the diameters of the conductors of the line to which said section is connected, said section conductors tapering 20 in opposite directions with such tapers as to produce on said transmission line unity standing wave ratio at the said mid-band operating frequency and having an electrical length equal substantially to an integral number of half- 25 wave-lengths at said mid-band frequency, and the other section having conductors tapering in the same direction from the dimensions of the conductors at the junction of said two sections to the dimensions of the conductors of the 30 line of known impedance having a conductor of known diameter.

If the outer or inner conductors of the two transmission lines to be coupled have the same radius it is thus desirable to taper both conductors of the coupling section impedance transformer in opposite ways from the diameters of the conductors of one transmission line for a half-wave-length of the said mid-band frequency and then in the same direction to the 40 diameters of the conductors of the other transmission line.

The invention will be further described in connection with the accompanying drawings in which:

45 Figs. 1 to 6 each show in longitudinal section an impedance transformer according to the present invention connecting together two coaxial conductor transmission lines of different conductor radial dimensions.

50 Fig. 7 shows several curves used in the description and

Fig. 8 shows a curve of Fig. 7 extended to greater limits than in Fig. 7.

Referring to the drawings, in Fig. 1 are shown 55 two coaxial conductor lines indicated as line 1

and line 2. The outer conductors 3, 4 of these two lines have different diameters as also the inner conductors 5, 6, and hence the lines have different characteristic impedances Z_1 and Z_2 respectively. These lines 1 and 2 are coupled by a coaxial line impedance transformer 7, 8 whose outer conductor 9 tapers from the larger conductor 3 to the smaller conductor 4 and whose inner conductor 10 tapers in the reverse direction from the larger conductor 6 to the smaller conductor 5. Such a general arrangement, however, does not provide a good impedance match between the lines 1 and 2.

If z is the impedance at 8 looking into the line 1, it can be shown that the additional impedance $z_1 = z - Z_1$ is a fluctuating function which tends to zero for a given $Z_1 - Z_2$ as the length e of the section tends to infinity. Furthermore, it can be shown that whether one or both conductors of the section 7, 8 is or are tapered, the added resistance r , is substantially zero when e is substantially equal to an integral number of half-wave lengths of the operating frequency and at these values of e the added reactance x is also a minimum. Hence to transform a coaxial transmission line to one of different characteristic impedance, the optimum length of connecting section to use is one whose electrical length is an integral number of half-wave-lengths at the operating frequency. Although the reactance X can be brought to a minimum by the use of a connecting section an integral number of half-wave-lengths long, it cannot be brought to zero if only one of the conductors is tapered. To make the reactance zero, it is necessary to taper both conductors in a uniquely determinate way, as will be explained hereinafter.

Usually, it is not sufficient to match impedances at a spot frequency, but it is required to have as good a match as possible over an appreciable band of frequencies.

As a criterion of goodness of match the standing wave ratio set up in the line 1 on the left of the drawings Figs. 1 to 6, the inner and outer conductors having radii R_1, R_2 respectively, by the introduction of the matching section will be considered. The standing wave ratio θ for any standing wave is the ratio of the maximum "root mean square" voltage measured at the voltage antinodes to the minimum "root mean square" voltage measured at the voltage nodes. It is well known from usual line theory that if a line of characteristic impedance Z_0 is terminated in an impedance $R+jX$, the standing wave ratio θ satisfies the equation

$$\frac{R}{Z_0} \left(\theta + \frac{1}{\theta} \right) = 1 + \frac{R^2}{Z_0^2} + \frac{X^2}{Z_0^2}$$

It will be observed that θ is a function only of the ratio R/Z_0 and X/Z_0 and does not depend on the absolute values of R and X . It can be shown that $z - Z_1$ remains unaltered if both Z_1 and Z_2 are increased while their difference remains unchanged, but the standing wave ratio which depends upon z/Z_1 will approach nearer to unity.

The input impedance Z_{in} to a quarter wave transducer, is given by:

$$\frac{Z_{in}}{Z_1} = \sqrt{\frac{Z_2}{Z_1}} \cdot \frac{\sqrt{\frac{Z_2}{Z_1}} \sec^2 \frac{2\pi e}{\lambda} + j \left(1 - \frac{Z_2}{Z_1} \right) \tan \frac{2\pi e}{\lambda}}{1 + \frac{Z_2}{Z_1} \tan^2 \frac{2\pi e}{\lambda}}$$

where e is the length of the transducer, and λ is the wave-length of the operating frequency. Thus the standing wave ratio which is a function

only of Z_{in}/Z_1 is in turn a function only of Z_2/Z_1 , and is thus the same for any pair of coaxial lines which have the same ratio of characteristic impedances Z_2/Z_1 .

This makes a perfectly general comparison with the quarter wavelength stepped uniform line transducer difficult, although it is always simple to compare any particular case in which Z_1 and Z_2 are given.

As an example, the case $Z_1=120$ ohms, $Z_2=70$ ohms, has been worked out for the quarter wave and three quarter wave stepped uniform line, see curves A and B, Fig. 7; for the tapered line with unchanged outer conductor, see curve C, Fig. 7; and for the doubly tapered line of optimum taper, see curves D and E, Fig. 7. The standing wave ratio θ is plotted against ne/λ where

$$n=4: \frac{4}{3}: 2: 2: 1$$

in the cases of curves A, B, C, D, E, Fig. 7 respectively. A more extended graph of curve E, Fig. 7, is given in Figure 8.

One or two points about these curves should be observed. In the first place it will be seen that the frequency band width regarded as a percentage of the central frequency remains unchanged when an optimum double-tapered section is increased from $\frac{1}{2}\lambda$ to λ see curves D and E. This is in contrast to the stepped uniform line transducer, where an increase in length from $\frac{1}{4}\lambda$ to $\frac{3}{4}\lambda$, curves A and B, reduces the bandwidth by a factor of 3. Another point to notice is that when only one of the conductors is tapered, the other remaining unchanged, curve C, it is impossible to achieve unity standing wave ratio. This is because the reactance cannot be made to vanish. However, the curve C of standing wave ratio against wavelength in this case is very flat, and for large enough departures from the central frequency the curve C crosses the curve A for the quarter wave stepped uniform line and thereafter lies below it. Thus for very wide band applications the singly tapered line is preferred to the stepped uniform line, for although the standing wave ratio is worse than for the stepped uniform line at the centre of the band, if the band is wide the standing wave ratio will be better at the edges of the band than for the stepped uniform line. Of course, if there is no objection to the slight extra trouble of tapering both conductors, curves D and E, the optimum doubly tapered line is better both at the centre and edges of the band, and is much to be preferred.

In designing the matching section the two impedances Z_1 and Z_2 between which to match and the size of either one or both of the lines will be known.

If only the size of the Z_1 line, say R_3 , is known, then, of course, R_1 is obtained by the well-known relation $Z_1=60 \log_e R_3/R_1$. If there is no restriction on R_2 and R_4 and R_2 are chosen such that

$$\frac{R_2}{R_1} = \frac{R_3}{R_4} = e^{(Z_1 - Z_2)/120}$$

where R_1 and R_3 are the radii of the inner and outer conductors of one line, impedance Z_1 , and R_2, R_4 the radii of the inner and outer conductors of the other coaxial line of characteristic impedance Z_2 .

If, however, R_2 is known then R_5 and R_6 (are first found) such that:

$$\frac{R_5}{R_1} = \frac{R_3}{R_6} = e^{(Z_1 - Z_2)/120}$$

where R_5 and R_6 are the radii of the inner and

outer conductors at the other end of the tapered section. This will give

$$\frac{R_6}{R_5} = e^{Z_2/60}$$

We then taper the inner and outer conductors from radii R_5 and R_6 to the radii R_2 and R_4 , with

$$\frac{R_2}{R_5} = \frac{R_4}{R_6}$$

In Figure 2 of the drawings is shown a case where the inner conductors of the two lines 1 and 2 to be coupled have different diameters as well as the outer conductors. The impedance transformer comprises two series connected sections the conductors having at their common connecting point, equal dimensions. One of the sections, in this case, the section 11 connected to the line 1 has the optimum length of one half the wavelength of the mid-band frequency the diameters of the conductors at the end of the section 13-14 being determined as hereinbefore described so that

$$\frac{R_5}{R_6} = e^{Z_2/60}$$

The conductors of the other section 12 are then tapered up from dimensions of R_5 and R_6 at the connecting plane 13-14 to dimensions R_2 and R_4 respectively such that

$$\frac{R_2}{R_5} = \frac{R_4}{R_6}$$

Thus if R_2 or R_4 is known, the other is determined accordingly.

It is still advisable to match in this fashion even if it is required to have $R_2=R_1$, $R_4=R_3$. That is, a conductor is not run straight through, even if the radius of one of the output conductors is the same as that of one of the input conductors. This procedure produces a lump on the inner conductor or a constriction in the outer conductor as shown in Figures 3 and 4 respectively.

In the embodiment shown in Fig. 3, the inner conductors of the two lines 1 and 2 have the same diameters, but the outer conductors have different diameters. In Fig. 4 the outer conductors have the same diameters but the inner conductors have different diameters. As in the case of Fig. 2, the sections 11 are given the optimum length of half a wavelength of the mid-band frequency but the section 12 may be of any convenient length.

It might be convenient mechanically to start from the low impedance and use a divergent cone initially as shown in Figs. 5 and 6.

The embodiments shown in Figs. 5 and 6 are the reverse cases of those shown respectively in Figs. 3 and 4. In all these cases, it will be observed that in the section 11 having the optimum length of half wave-length the inner and outer conductors taper in opposite directions while in the section 12, the inner and outer conductors taper in the same direction. The lengths of the sections 12 are shown as being different in all four cases, since there is no restrictive condition on this length.

There is nothing to choose between the arrangements shown in Figs. 3 and 4 or 5 and 6 from electrical considerations.

The lengths of the tapered sections, in which the tapering is in the opposite sense in the two conductors, may be of course made an integral number of half wave-lengths long, but there is

little to be gained by using more than one half wave-length. In the sections where the tapering is in the same sense in the two lines, i. e. where mere scaling up or down is carried out, there is no restriction to half wavelength sections. These latter sections may be of any length.

What is claimed is:

1. An impedance matching section for transforming over a wide band of operating frequencies the impedance of a coaxial conductor transmission line to the impedance of another coaxial conductor transmission line comprising a section of tapered coaxial conductor transmission line having conductor diameters at one end equal to the diameters of the conductors of one of the lines to which said section is to be connected, said section conductors tapering in opposite directions and having an electrical length equal substantially to an integral number of half wave-lengths at the mid frequency of the operating band, said section conductors further tapering in the direction to the diameters of the other line to which the section is to be connected.
2. An impedance matching transformer for transforming over a wide frequency band the impedance of a coaxial conductor transmission line to a given impedance coaxial conductor line having one conductor of predetermined diameter comprising two series connected sections of tapered coaxial transmission lines, one of said sections having conductors tapering in opposite directions and having an electrical length equal substantially to an integral multiple including unity, of one half wave-length at the mid-frequency of the operating band and the other section having conductors tapering in the same direction from the dimensions of the conductors at the junction of said two sections to the dimensions of the conductors of the line to which said other section is to be connected.
3. An impedance transformer for transforming over a wide frequency band, the impedance Z_1 of a coaxial conductor transmission line to the impedance Z_2 of another coaxial conductor transmission line of which the diameter R_2 or R_4 of the inner or outer conductor is known, comprising two series connected sections of coaxial transmission line, one of said sections having conductors tapering in opposite directions to diameters R_5 and R_6 at the common junction point of the two sections from the end of said transmission line of impedance Z_1 so that $R_6/R_5 = e^{Z_2/60}$ and having a length substantially equal to an integral multiple including unity of half a wave-length at the mid-band operating frequency, and the conductors of the other section tapering in the same direction from R_5 , R_6 to the diameters R_2 , R_4 of the inner and outer conductors respectively of the other transmission line in such manner that $R_2/R_5 = R_4/R_6$.
4. An impedance matching section for transforming the impedance Z_1 of a coaxial conductor transmission line having conductors of diameters R_1 and R_3 to an impedance Z_2 of another coaxial conductor transmission line having conductors of diameters R_2 and R_4 by transforming the diameters of the inner and outer conductors respectively, comprising a section of coaxial transmission line having conductors whose diameters at one end are equal respectively to R_1 and R_3 and which taper in opposite directions to diameters R_5 and R_6 respectively, said section having an electrical length equal to

an integral number of half wave lengths at the operating frequency, the diameters R_5 , R_6 being such that

$$\frac{R_6}{R_5} = e^{\frac{Z_0}{60}}$$

and a second section of coaxial transmission line having conductors whose diameters at one end are equal respectively to R_5 and R_6 and which 10 taper to diameters R_2 and R_4 .
